P. MUELLER ET AL

BUILT-IN REMOVABLE VALVE

Filed Nov. 20, 1926

UNITED STATES PATENT OFFICE.

PHILIP MUELLER, ROBERT H. MUELLER, AND WILLIAM J. MIX, OF DECATUR, ILLINOIS, ASSIGNORS TO ADOLPH MUELLER, TRUSTEE, OF DECATUR, ILLINOIS.

BUILT-IN REMOVABLE VALVE.

Application filed November 20, 1926. Serial No. 149,741.

The present invention relates to improvements in valves, particularly of the type designed for use with built-in bath fixtures.

Considerable trouble has been experienced with valve devices of built-in bath fixtures in which the valve seats are commonly located within, or in rear of, a wall so that it is quite difficult to have access thereto for repairing or replacing worn parts.

By the present invention means are provided whereby the valve seat and cooperating valve of such a fixture may be readily removed as a unit, and, further, means are provided whereby the removal of one of a series of valves of such a fixture will not necessarily render the entire fixture temporarily useless.

With the foregoing and other objects in view, the invention consists in the construction and arrangement of parts that will be hereinafter more particularly described, reference being had to the accompanying drawing, in which:—

Figure 1 is a more or less diagrammatic view of a built-in bath fixture containing an embodiment of the present invention.

Figure 2 is a sectional view, on an enlarged scale, through one of the improved valve structures.

Figure 3 is a view of the valve devices detached from the body of the valve.

Figure 4 is a section substantially on the line 4—4 of Figure 2.

Referring to the drawings, the bath fixture illustrated comprises hot and cold water supply pipes 1, 2, a tub spout 3, and a supply pipe 4, for a shower head, not shown.

The supply of water to the tub spout 3 is, as usual, controlled by valves 5, 6, while the flow of water to the shower head supply pipe 4 is controlled by similar valves 7, 8.

It will be understood that all of these control valves may be of the construction specifically illustrated in Figures 2, 3 and 4, each comprising a body provided with suitable inlet and outlet ports and having a lateral extension 10, which, as shown, extends outward slightly beyond the face of the wall 11, in which the valve is supported.

As shown, the opening in the wall 11, within which the valve body is positioned, or through which the lateral extension 10 thereof projects, is of slightly greater diameter than said lateral extension, although, if

preferred, the body of the wall may closely surround said extension.

Within the body of the valve a partition 12 separates the inlet and outlet ports, in the usual manner, a suitable aperture being formed in said partition through which communication between said ports may be established.

As shown, the opening through the partition 12 is threaded and the reduced end 13 of a valve casing 14 is engaged with such thread. The valve casing 14 is provided interiorly with a suitable valve seat 15 with which is adapted to cooperate a valve 16, the stem 17 of which extends outward through the valve casing and the surrounding lateral extension 10 of the body of the valve.

Ports 18 are provided in the wall of the valve casing 14, and when the valve 15 is properly adjusted water is permitted to flow from the inlet port of the valve body 75 through the opening in the partition 12 and said ports to the outlet port of the valve body in the ordinary manner.

As shown, the valve stem 17 is provided with a threaded section 20 that engages a suitable thread formed interiorly of the valve casing, and at its outer end said valve stem is provided with an ordinary removable handle 21. To prevent leakage past the valve stem a suitable packing 25 is provided, 85 the same being positioned between a washer 26 that cooperates with a seat formed on the inner face of the wall of the casing 14 and a similar washer 27 which is adjustably held in position by a socketed plug 28, which is 90 screwed into the outer end of the casing 14, being held in any adjusted position by the threaded joint 29.

Adjacent its outer end the valve casing is provided with an exteriorly knurled section 30 by which it may be engaged to permit its being rotated to disengage it from the partition 12 when it is desired to withdraw the same from the body of the valve.

A similar knurled surface 31 is preferably provided on the plug 28 to assist any adjustment of this element to properly compress the packing 25, as will be obvious.

When the valve casing 14 is engaged with the partition 12 in the valve body, it is accurately centered or held in proper axial relation to the lateral extension 10 by an annular rib 40 that extends inward from the

wall of said extension of the valve body. The outer face of this rib 40 constitutes a seat for a packing 41 which is suitably compressed by a sleeve 42 that engages an internal thread at the outer end of the lateral extension 10 of the valve body. Preferably a washer 43 is interposed between the inner end of the sleeve 42 and the packing 41.

A suitable escutcheon 45, commonly made 10 of vitreous material, is provided for surrounding the outer ends of the valve body and valve casing, said escutcheon being retained in position by a cap member 46 which surrounds the valve stem 17 and has a tubular portion 47 engaging a thread within the socket at the outer end of the aforesaid plug 28.

It is believed that the operation of the several parts will be readily understood from 20 the foregoing description in connection with the drawing. As shown, the valve casing and valve therein may be detached as a unit from the valve body without requiring any relative movement between the same and its 25 associated supply and delivery pipes.

The parts being assembled as shown in Figure 2, if it becomes necessary to have access to the valve 16 or the seat 15 therefor within the valve casing it is only necessary 30 to detach the handle 21 and escutcheon cap 46 when the escutcheon may be removed. This exposes the securing sleeve 42, which can be easily disconnected and then by engaging the knurled section 30 of the valve 35 casing 14, the latter can be unscrewed from the partition 12 in the valve body and bodily withdrawn, as shown in Figure 3.

In case it is not practicable to immediately restore the valve casing after such removal, and yet be desired to use the fixture of which the valve forms a part, it is only necessary to screw a suitable pipe nipple into the lateral extension of the valve body and insert a plug therein to prevent escape 45 of water. In other words, the removal of one of the valves of such a fixture as is diagrammatically illustrated in Figure 1, when the valves are constructed in accordance with the present invention, does not render 50 the entire fixture useless.

Another important feature or advantage secured by the present invention is that in installing the fixture all of the parts, with the exception of the bodily removable valve 55 casing 14 and parts therein, may be properly assembled and by substituting suitable nipples as above described, tested before the actual valve structures are themselves inserted. This avoids any danger of such parts 60 being stolen as is of frequent occurrence in plumbing installations.

It will be understood, of course, that in the drawing the parts are shown more or less conventionally, and that there can be

modification as to some of the details without departing from the invention.

Having thus described the invention, what is claimed as new is:

1. A plumbing fixture comprising a valve body provided with inlet and outlet ports and an interior partition between said ports and having a threaded aperture formed therein, a valve casing provided with a valve seat and a threaded section engaging the thread of said aperture in the partition in the valve body, said casing being provided between its outer end and the section engaging the partition with a lateral port and between said port and its outer end with an internal thread, means providing a fluid tight joint between the valve body and said casing, and a valve adapted to cooperate with the valve seat and having its stem extending through the outer end of the casing and provided with a compression thread engaging said interior thread in the casing, whereby the valve casing and valve may be removed from the body as a unit, for the purpose described. 70 75 80 85

2. A plumbing fixture comprising a valve body provided with inlet and outlet ports and having a lateral extension that projects therefrom in position to be received in an opening in a wall, the valve body being provided with an interior partition extending transversely of said lateral extension and separating said inlet and outlet ports, a valve casing detachably supported within the lateral extension of the valve body and communicating with an opening in said partition, said casing being provided with an interior, outwardly facing, valve seat and provided between said seat and its outer end, with an interior thread, an aperture being formed in the wall of the casing between 90 95 100 105 110 115 120 said interior thread and the valve seat, an annular rib extending inward from the lateral extension of the valve body, packing resting on said rib and forming a fluid tight joint between the said extension of the valve body and said casing, an adjustable sleeve for maintaining said packing under compression, a valve adapted to cooperate with the seat in the casing and having its stem extending beyond the outer end of the casing and provided with a compression thread engaging the thread in the casing, and means for maintaining a fluid tight joint between the valve stem and casing, the parts being so arranged that the valve casing and valve may be readily removed as a unit from the valve body. 120

In testimony whereof we have hereunto set our hands.
